SPATULA MILL

Leslie W. Claybourn and Edward A. Butler, Buffalo, N. Y., assignors to The Turbuletics Corporation, Buffalo, N. Y.

Application October 8, 1940, Serial No. 360,306

3 Claims. (Cl. 83—7)

This invention relates to mills for grinding and/or mixing of materials, and particularly to processing mills adapted to efficiently mix relatively viscous and/or sticky materials, for example, as in connection with the preparation of colored printing inks, or the like.

One of the objects of the invention is to provide an improved mill for the purpose described comprising essentially a stationary milling member and a rotary milling member wherein the relative disposition of the milling members is adjusted and maintained by improved means. Another object of the invention is to provide a mill of the character described which is of improved capacity and operating efficiency, and structurally simple and rugged. Other objects and advantages of the invention will appear in the specification.

In the drawing:

Fig. 1 is a plan, with portions broken away, of a mill of the invention;

Fig. 2 is a section taken substantially along line II—II of Fig. 1;

Fig. 3 is a section through a stator-supporting portion of the mill; and

Fig. 4 is a transverse section through the stator supporting portion of Fig. 3.

The mill comprises essentially a base 10 upon which is mounted an annular side wall or housing 12 which is spanned across its top center by a beam 14. An upright post 16 is rigidly mounted upon the base 10 at the center of the mill, and a milling rotor 20 is rotatably mounted upon the post 16 by means of bearings 22. Gear means are illustrated at 24 for supplying power to the rotor.

The milling surface portion of the rotor 20 is of conical form concentrically of the axis of rotation, and is preferably lined with a similarly shaped wearing plate 26 to take the wear of the milling action. A milling stator 30 is disposed adjacent the milling face of the rotor 20 and is detachably mounted above the rotor within the housing 12 in such manner as to press the mill feed material against the rotor when passing therebetween. The stator 30 is maintained against rotation within the frame 12 by means of a plurality of connecting pins 32 which are disposed at spaced intervals about the periphery of the stator. The pins 32 are of rod like form and rounded at their opposite ends so as to be adapted to pivot vertically at their respective ends within corresponding sockets formed in the stator and housing wall portions. As illustrated in Figs. 3 and 4, the sockets 34 in the

housing 12 and the sockets 36 in the stator 30 are of funnel-like form in vertical planes so as to permit relative movement between adjacent portions of the housing 12 and the stator 30 in vertical directions only, as illustrated in broken and solid lines in Fig. 3.

As illustrated in Fig. 4, however, the sockets fit the pins 32 closely at their sides. Consequently, the pins are free to move vertically so as to permit relative movement in vertical directions between adjacent portions of the stator and the housing 12; but rotation of the stator relative to the housing is prevented. Preferably, the pins 32 are so constructed as to be adapted to shear under predetermined excessive load conditions, whereby they are adapted to function as safety devices to relieve the operating portions of the mill in case the rotor and stator become locked together under abnormal service conditions.

The stator 30 is provided with a central stem 40 which is bored as at 42 to provide the mill feed inlet conduit for the device, and it will be understood that the upper end of the stem 40 will be connected to the mill feed supply means in any suitable manner. At its lower end the stem 40 opens into the space between the rotor and the stator at the apex of the milling zone therebetween, and the mill feed material is thus introduced into the milling zone at the center thereof for movement radially under the combined forces of gravity and centrifugal action due to rotation of the rotor. The stator is adjustably mounted upon the housing 12 by means of a thrust collar 44 which is screw-threaded into a central portion of the beam 14 and is internally bored so as to receive the stem 40 therethrough. A compression spring 46 is disposed between the stator 30 and the adjacent end of the thrust collar 44 so that the stator may be adjusted to press resiliently downwardly upon the rotor in response to screw-threaded adjustments of the thrust collar 44 relative to the beam 14. Laterally extending handles 48 are formed upon the thrust collar 44 for the convenience of the operator in adjusting the pressure upon the stator.

The bore of the thrust collar 44 and the outside diameter of the stem 40 are so relatively proportioned as to provide a substantial gap 50 therebetween. Consequently, the stator 30 and its integral stem portion 40 are free to oscillate within the thrust collar 44, as for example whenever the volume of the mill feed material between the rotor and the stator varies at op-

posite sides of the center of the mill. Consequently, under such conditions the stator will be free to move upwardly and away from the rotor at the position of increased bulk of mill feed material, as illustrated diagrammatically in Fig. 3, and without interference between the stem 40 and the thrust collar 44. Consequently, the spring 46 normally imposes equal pressure forces at all sides downwardly upon the stator, and the stator floats freely upon the mill feed material and adjusts itself in accord with variations in the volume and distribution of the mill feed material; but the spring 46 tends at all times to return the stator to normal attitude and parallel to the working face of the rotor.

The stator 30 is preferably regulated as to temperature by means of a temperature regulating fluid introduced through an inlet 60 for transmission through intercommunicating fluid chambers 62 formed within the stator structure, and thence through an outlet conduit 64. The stator 30 is also preferably reinforced by means of radial fins 68 at the outer surface thereof to increase the rigidity of the structure. At intervals about the inner wall of the housing 12 are provided a plurality of laterally extending scraper plates 70 which are mounted in cantilever fashion upon the housing 12 and extend therefrom into scraping contact with the periphery of the rotor 20. These scrapers 70 function to scrape the product of the mill away from the periphery of the working surfaces thereof as the product exudes from between the milling members. Appropriate troughs (not shown) may be disposed beneath the scrapers 70 to receive and convey away the product of the mill.

Although only one form of the invention has been shown and described in detail, it will be apparent to those skilled in the art that the invention is not so limited but that various changes may be made therein without departing from the spirit of the invention or the scope of the appended claims.

We claim:

1. A processing mill comprising essentially a frame, a rotor rotatably mounted upon said frame, a stator universally mounted upon said frame by means of an elastic compression connection device in opposed relation with respect to said rotor whereby said stator is adapted to oscillate relative to said rotor about substantially horizontal axes under unevenly distributed loadings therebetween, means for introducing mill feed material between said stator and said rotor, means for imparting rotational movements to said rotor, and a pin extending between said frame and said stator and disposed at its opposite ends in sockets formed in said stator and said

frame, said sockets being elongated in directions parallel to the axis of rotation of said rotor to permit said pins to accommodate movements of said stator in directions parallel to said axis of rotation, said sockets being otherwise closely fitted to said pin whereby said pin prevents rotation of said stator relative to said frame.

2. A processing mill comprising essentially a frame, a rotor rotatably mounted upon said frame, a stator mounted upon said frame by universally elastic connection means in opposed relation with respect to said rotor whereby said stator is adapted to oscillate relative to said rotor about substantially horizontal axes under unevenly distributed loadings therebetween, elastic force means mounted upon said frame and said stator to urge said stator against said rotor, adjustment means operatively associated with said elastic force means for varying the force exerted thereby, means for introducing mill feed material between said stator and said rotor, means for imparting rotational movements to said rotor, and a free pin disposed to extend between said frame and said stator and having its opposite ends disposed in sockets formed in said stator and said frame, to prevent rotation of said stator relative to said frame.

3. A processing mill comprising essentially a frame, a rotor rotatably mounted upon said frame, a stator mounted upon said frame by universally elastic connection means in opposed relation with respect to said rotor whereby said stator is adapted to oscillate relative to said rotor about substantially horizontal axes under unevenly distributed loadings therebetween, elastic force means mounted upon said frame and said stator to urge said stator against said rotor, adjustment means operatively associated with said elastic force means for varying the force exerted thereby, means for introducing mill feed material between said stator and said rotor, means for imparting rotational movements to said rotor, said mill feed introducing means being in the form of a tubular structure integral with said stator and extending through said frame at a loosely fitting portion thereof, said elastic connection means being in the form of a compression spring mounted upon said tubular feed inlet and bearing at one of its ends against said frame and at the other of its ends against said stator, and a free pin disposed to extend between said frame and said stator and having its opposite ends disposed in sockets formed in said stator and said frame, to prevent rotation of said stator relative to said frame.
